(57) **CLAIM**

The ornamental design for the pair of handles for aviation snip tool, as shown and described.

DESCRIPTION

FIG. 1 is a perspective view of the aviation snip handles.

FIG. 2 is a left side view of the handles of FIG. 1. The right side view of the handles is a mirror image of the left side view of the handles.

FIG. 3 is a top plan view of the handles of FIG. 1; and,

FIG. 4 is a bottom plan view of the handles of FIG. 1.

The broken lines shown in the drawings represent environmental structure and form no part of the claimed design.
